Primary Examiner — Richard E Chilcot*(74) Attorney, Agent, or Firm* — Sughrue Mion, PLLC(57) **CLAIM**

The ornamental design for a inkjet printer, as shown and described.

DESCRIPTION

FIG. 1 is a front, top and right-side perspective view of an inkjet printer showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is an enlarged view of the area **8** indicated by the double dot-dash broken lines in FIG. 1.The evenly-spaced broken lines depict portions of the inkjet printer that form no part of the claimed design. The single dot-dash broken lines define the boundary of the claimed design and form no part of the claimed design. The rectangle indicated by the double dot-dash broken lines shown in FIG. 1 and FIG. 8 illustrate the boundary of enlarged area of the design. The “**8**” indicia and splined curve indicated by the double dot-dash broken lines in FIG. 1 identify the enlarged area. None of the broken lines form any part of the claimed design. The gray surface shading in FIG. 1, FIG. 2, FIG. 5 and FIG. 8 represents a contrast in appearance only and does not represent any particular color, material, texture, or finish.**1 Claim, 5 Drawing Sheets**(56)
